UNITED STATES PATENT OFFICE.

CARLOS M. BIEDMA, OF BUENOS AIRES, ARGENTINA.

SCHOOL-BENCH.

1,276,713.

Specification of Letters Patent. Patented Aug. 27, 1918.

Application filed March 6, 1918. Serial No. 220,775.

To all whom it may concern:

Be it known that I, CARLOS M. BIEDMA, a citizen of the Argentine Republic, residing at No. 3310 Santa Fe st., Buenos Aires, Argentina, have invented certain new and useful Improvements in School-Benches, of which the following is a specification.

This invention relates to certain new and useful improvements in school benches and 10 has for its object to provide a school bench of simple construction and adapted to various uses.

A further object of the invention is to provide a school bench the height of which 15 may be regulated at will, the seat and desk being independently and movably mounted on a common support.

In order that the invention may be clearly understood and easily carried into practice, 20 it will now be described with reference to the accompanying drawings in which:—

Fig. 1 is a perspective view of a school bench according to the present invention.

Fig. 2 is a central sectional elevation of 25 the same with the desk and drawer in its closed position.

Fig. 3 is a sectional detail of the desk in one of its open positions and

Fig. 4 shows the desk and drawer in an 30 alternative position.

Similar characters refer to the same or like parts throughout the above figures.

5 and 6 are two vertical supports of wood, cast iron or any other convenient material 35 which at their lower ends are connected by a transverse piece 7. Said supports 5 and 6 are provided at their inner sides with two parallel guideways 8 and 9 in which frames 10 and 11 carrying respectively the seat 12 40 and the desk and drawer may be slidably mounted.

The seat carrying frame consists of two lateral supports suitably connected to each other and having a longitudinally disposed 45 slot 13 which allows setting the frame at any desired height, by means of a screw and nut connection. Said screw and nut, indicated at 14, are introduced through an orifice made in the front guide-way 8, the nut being 50 screwed on when the frame has been placed at the desired height.

The rear guide-way 9 is provided with a series of longitudinally disposed holes 15, which by means of a pin 16 or the like allow 55 the height of the desk-and-drawer carrying

frame 11 to be conveniently regulated, independently of the height of the front frame.

This rear frame 11 consists of two side members 17 and 18 connected at their upper and lower ends by means of transverse 60 boards 19 and 20, the upper one being used as an inkstandholder. The outer faces of the sides 17 and 18 are provided with extensions or bosses 21 and 22 respectively which run in the longitudinal guide-ways 9 65 of the main supports 5 and 6.

A case or drawer 23 has its sides 24 pivotally connected near their upper end, as at 25, to the sides 17 and 18 of the frame 11. A small board 26 hinged at 27 is held closed by 70 means of a hook 28 and allows the drawer 23, when in its vertical position, to be used as a bookstand.

Another board 29 is pivotally mounted at 30 to the sides 17 and 18 of the frame 11 75 above the board 19, and at the rear of the same. This board 29, when in its vertical position acts as a cover or lid for the said drawer 23. The drawer 23 may be placed at different angles and firmly secured in position by means of two lateral supports 31 articulated to the outer sides of the drawer walls 24. Said supports 31 are each provided with teeth engaging with a stop 32 fixed to the inner sides of the frame sides 80 17 and 18.

As may be seen from the foregoing description and from the accompanying drawings, the board or table 29 may be firmly secured in different positions in which it 90 may be used as a desk (Fig. 3) or as an extension of the open drawer 23, when this latter is used for handy work.

As may be easily understood the height of the desk and the height of the seat may 95 be independently regulated within a large range, which allows the bench to be used by pupils of very different ages and sizes.

Constructional modifications may be introduced without departing from the spirit 100 of the invention which is clearly set forth in the annexed claiming clauses.

What I claim is:

1. In a school bench, the combination of a pair of spaced, parallel vertical supports 105 having their inner sides provided with front and rear longitudinal guides, the guides on one support being disposed opposite those on the other support; connecting means between said supports; a frame disposed be- 110

2
 tween said supports and slidably engaging the front guides; a seat carried by said frame; means for retaining said frame in adjusted position; a frame, separate from the first-named frame, disposed in rear thereof between said standards and slidably engaging the rear guides so as to be adjustable independently of and relatively to said first-named frame; means for retaining the second-named frame in adjusted position; a drawer pivoted to said second-named frame for bodily swinging movement independently of and relatively to that frame; said drawer having means for releasably supporting it in substantially horizontal position and adapted to swing downwardly into vertical position between the sides of said second-named frame; and a pivoted cover for said drawer movable into position to open or close the same in either of its said positions.

2. In a school bench, the combination of a pair of spaced, parallel vertical supports having their inner sides provided with oppositely-located, longitudinal guides, connecting means between said supports; a frame disposed between said supports and comprising a pair of vertical side members arranged against said supports and slidably

engaging said guides, and upper and lower cross-pieces connecting said side members; means for retaining said frame in adjusted position; a swinging drawer having its sides pivoted to the frame sides slightly below the upper cross-piece; means for releasably supporting said drawer in substantially horizontal, rearwardly-extending position; and a board hinged to said frame sides above and to the rear of said upper cross-piece to swing with relation to the drawer forwardly into a position in which it extends forwardly across and rests upon said upper cross-piece, or rearwardly into a position in which it extends over and rests upon said drawer when the latter occupies its rearwardly-extending horizontal position; said drawer being adapted to swing downwardly into the space between said upper and lower cross-pieces, and said board to swing downwardly relatively to said drawer into position to act as a cover therefor.

In testimony whereof I affix my signature in the presence of two witnesses.

CARLOS M. BIEDMA.
